United States Patent Office

Des. 197,424
Patented Jan. 28, 1964

197,424

COOKING, WARMING, AND VENDING UNIT FOR FOOD

Otto E. Werner, Skokie, Ill., assignor to Automatic Canteen Company of America, Chicago, Ill., a corporation of Delaware

Filed Sept. 25, 1961, Ser. No. 66,848

Term of patent 14 years

(Cl. D81—10)

FIG. 2.

FIG. 3.

FIG. 4.

FIGURE 1 is a perspective view of a cooking, warming, and vending unit for food embodying my new design;

FIGURE 2 is a perspective view showing the opposite sides of FIGURE 1;

FIGURE 3 is an enlarged fragmentary perspective view taken from the upper right of FIGURE 2; and

FIGURE 4 is a fragmentary elevational view taken from the right of FIGURE 2.

I claim:

The ornamental design for cooking, warming, and vending unit for food, as shown.
